RICHARD A. WILLIAMS AND WALTER L. BIGSBY, OF BELOIT, WISCONSIN, ASSIGNEES
TO YATES-AMERICAN MACHINE COMPANY, OF BELOIT, WISCONSIN, A CORPORA-
TION OF DELAWARE.

SANDER DRUM.

Application filed March 6, 1926. Serial No. 92,672.

This invention has to do with sander drums of the type in which the covering of sand paper or other material is wound spirally on the drum.

5 The principal object of the invention is to provide, in such a drum, an improved mechanism for initially tensioning the covering on the drum and thereafter taking up the slack which develops in the covering 10 while in service.

Other objects and advantages of the invention will be evident upon a full understanding of the construction, arrangement and operation of the mechanism.

15 One form of the invention is herein presented for the purpose of exemplification, but it will be understood that the invention is also susceptible of embodiment in other modified forms coming equally within the 20 scope of the appended claims.

In the accompanying drawing, Fig. 1 is a sectional view through a drum equipped with the mechanism of the invention, Fig. 2 is a somewhat similar view produced on a 25 larger scale, and Fig. 3 is an axial view of the drum with the near end plate removed.

The drum illustrated in the drawing consists of a shaft 10, a number of cylindrical 30 sections 11 which are fixedly mounted on the shaft, and two end plates 12 and 13 which are loosely mounted on the shaft at the ends of the sections. The covering of sand paper or other material (not shown) 35 is wound spirally about the body of the drum over a lining of felt or other material (also not shown), and is secured in a suitable manner to the peripheral portions of the end plates 12 and 13, which plates are 40 so mounted on the shaft as to be movable spirally therealong in opposite directions whereby to place the covering under tension.

A gear 14 is journalled on the hub 15 of 45 the section which adjoins the end plate 12, and is provided with a sleeve 16 which is in screw-threaded engagement with the hub 17 of the end plate 12. Another gear 18 is journalled on the hub 19 of the section which 50 adjoins the other end plate 13, and is provided with a sleeve 20 which is in screw-threaded engagement with the hub 21 of an intermediate plate 22. The plate 13 is held in spaced relation to the plate 22 by means

55 of a number of compressed coil springs 23, which springs encompass studs 24 screwed into the plate 13 and seat within cup-shaped casings 25 carried by the plate 22 over apertures therein. The studs 24 pass through apertures in the bottoms of the casings 25, 60 and are headed over beyond the bottoms whereby to engage therewith and limit the extent to which the springs 23 can separate the plate 13 from the plate 22.

The threads 26 between the gear 18 and 65 the intermediate plate 22 are opposite in direction to the threads 27 between the gear 14 and the end plate 12, and are substantially greater in pitch, the pitches being preferably in about the ratio of two to one. It is 70 in this feature of the mechanism that the invention primarily resides.

Each of the end plates 12 and 13 is provided with a projection 28 which extends 75 within the body of the drum and is diagonally slotted at 29 to engage with a stud 30 on the inner wall of the body. The pin and slot connections described cause the end plates 12 and 13 to move spirally in opposite directions away from the body of the drum when separative movement is imparted thereto by rotation of the gears 14 and 18. Two small pinions 31 and 32 mesh respectively with the gears 14 and 18, and are 80 fixedly mounted on a shaft 33 which is journalled in the body of the drum. One end of the shaft 33 is positioned just inwardly of the end plate 13, and is provided with a polygonal portion 34 which may be engaged by a socket wrench inserted 85 through an aperture 35 in the plate 13.

It is quite important that the weight of the parts of the mechanism in the drum be counterbalanced relative to the axis of rotation, and the weight of the pinions 31 and 32 and shaft 33 at one side of the drum is accordingly neutralized by the weight of a rod 36 which is positioned in the drum in diametrically opposed relation to the shaft 33. The rod 36 also serves as a support for 100 two gear-positioning members 37 and 38 which are adjustably mounted on the ends of the rod and bear against the outer side faces of the gears 14 and 18 whereby to position the same on the hubs 15 and 19.

105 When the shaft 33 is rotated in a clockwise direction, as viewed in Fig. 3, the pinions 31 and 32 will cause the gears 14 and

18 to rotate in a counterclockwise direction. The gear 14 will thereupon screw the end plate 12 outwardly in a spiral clockwise path defined by the pin and slot connection between the plate and the body of the drum, and the gear 18 will screw the intermediate plate 22 outwardly, causing the plate 22 to push before it the end plate 13 in a spiral counterclockwise path. The plate 22, however, will move at a much greater rate of speed than the plate 12 because of the difference in pitch between the threads on the gear 14 and those on the gear 18, with the result that the end of the covering attached to the plate 13 will receive the proper amount of tensioning before the end attached to the plate 12 does, and the springs 23 between the plates 13 and 22 will as a consequence yield as the plate 22 continues to move outwardly.

When the covering has received the proper amount of tensioning throughout the length of the drum, the drum is ready for use. After the drum has been in service for a time, slack will tend to develop toward the rear end of the spirally wound covering, which end is attached to the plate 13, but, as fast as such slack develops, it will be automatically taken up by further spiral movement of the plate 13 under the expanding action of the compressed springs 23.

We claim:

1. A sander drum, comprising a body on which a covering of sand paper or other material is adapted to be spirally wound, a member to which one end of the covering is adapted to be secured, another resiliently yieldable member to which the other end of the covering is adapted to be secured, and means for moving the members spirally in opposite directions with the resiliently yieldable member moving at a greater rate of speed than the other member.

2. A sander drum, comprising a body on which a covering of sand paper or other material is adapted to be spirally wound, two members to which the ends of the covering are adapted to be secured, connections between the members and the body for limiting the members only to spiral movement in opposite directions relative to the body, two gears journaled within the body, means operable from exteriorly of the body for rotating the gears, a screw-threaded connection between one gear and one member, and a screw-threaded connection of substantially greater pitch between the other gear and the other member.

In testimony whereof we have hereunto subscribed our names.

RICHARD A. WILLIAMS.
WALTER L. BIGSBY.
